UNITED STATES PATENT OFFICE

2,349,920

DIE

Carl J. Welcome, Toledo, Ohio

Original application August 19, 1940, Serial No. 353,195. Divided and this application August 25, 1941, Serial No. 408,182.

3 Claims. (Cl. 18—47)

My invention relates to the art of duplicating objects and particularly to the fabrication of molds, tools and dies for accurately reproducing objects irrespective of intricacy of design or form, and is a division of my copending application, Serial No. 353,195, filed August 19, 1940.

The invention comprehends simple, inexpensive dies, tools and molds for duplicating objects to exact form and dimensions, eliminating tedious and time consuming operations which require a high degree of skill.

The invention includes the provision of a die or cavity mold formed of an exceedingly hard metal which will withstand heat, abrasion and corrosion and which can be readily and inexpensively reconditioned without the necessity of complicated machine operations.

It is an object of my invention to provide improvements in the manufacture of molds, tools and dies which makes very easy and rapid production of cavity molds of intricate design for the molding of plastics, glass, and metals which heretofore have been impossible or too costly to be machined out.

It is an object of my invention to provide a mold or die that will resist heat, abrasion and corrosion, including means to indicate wear and which may be reconditioned and used again.

It is an object of my invention to make molds or dies having a low coefficient of expansion and which are more resistant to heat, abrasion and most chemical reactions, than are dies now made of tool steel or alloy steel.

It is an object of my invention to accomplish the making of tools and dies by unskilled workmen which will be an accurate replica of the model by electrodepositing metallic layers on the surface of the model.

It is an object of my invention to produce a die formed of superimposed metals wherein the face metal exposed to wear is bonded to an underlying or foundation metal, the latter being capable of withstanding without deterioration the removal of the face metal.

It is an object of my invention to produce a die by depositing on a fundation layer or metallic structure, having the shape of the working surface of the die, a hard metal to form a backing which also takes the shape of the working surface of the die.

It is an object of my invention to make molds, tools and dies by workmen of ordinary skill in a shorter time than has heretofore been required, eliminating the slow and laborious opera-

tion of hobbing out, and hand tooling which is necessary at the present time.

It is an object of my invention to make molds and dies of metallic layers which are deposited electrically or otherwise upon the surface of the object to be duplicated including: a hard metal capable of being stripped and reconditioned forming the face or working surface; a softer metal preferably of the base metal type capable of withstanding the removal or stripping operation of the face metal without deterioration constituting the foundation metal or metallic shell having the shape of the working surface; a primary base substantially of the same metal as that face, having toughness, hardness, heat resistance and shock resistance; and a secondary base of malleable or softer metal which can be applied mechanically and shaped to conform to the press or machine used for operating the die.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

Figure 1 is a side elevational view with a portion in section of a pattern or article to be duplicated in accordance with the method of my invention;

Figure 2 is a sectional view illustrating the die block produced in accordance with my improved method for duplicating articles;

Figure 3 is a sectional view illustrating the upper element of the die block illustrated in Figure 2;

Figure 4 is a cross sectional view of the article to be duplicated, illustrating that a portion of the surface to be duplicated is coated with a current conductive substance.

Figure 5 represents the step of my improved method in establishing the surface to be duplicated as a cathode in an electro-plating bath;

Figure 6 is a cross-section of the article illustrating the built up foundation shell produced by an electro-plating bath;

Figure 7 represents the step of my improved method in establishing the deposited shell as a cathode in an electro-plating bath for depositing a reinforcing backing or primary base there-to;

Figure 8 illustrates the backed electro-plated

shell after the same has been removed from the surface of the article to be duplicated;

Figure 9 illustrates the step of my improved process in applying the die face to the electro-plated shell by establishing the same as a cathode in an electro-plating chromium bath;

Figure 10 is a sectional view of the electro-plated shell with a suitable base or support to form one of the component elements of the composite die block.

The principles of the invention are illustrated in their practical application to the fabrication of a composite die block used for duplicating an article by utilizing a synthetic plastic material. However, the invention is not limited to this particular application but the same comprehends the employment of the principles hereinafter enumerated for producing tools for reproducing surface contours or articles utilizing metals or other types of materials.

My invention for duplicating articles by producing a forming tool such as a die or mold in one of its general aspects includes the production of a die by superimposing several metals having certain characteristics. The metal exposed to wear constituting the face of the forming tool or die is exceedingly hard, able to resist heat abrasion, corrosion and having a long wearing surface. The face metal is bonded to, or deposited upon a foundation metallic shell or upon a primary reinforcing metallic base. The foundation shell is formed or made of a metal somewhat more ductile having a different color characteristic than that of the face metal and capable of withstanding without impairment the removal of the face metal. The foundation shell is preferably produced by the deposition of a suitable metal upon the surface to be duplicated to take the shape of the same. This foundation shell is bonded to or reinforced by a metallic primary base suitably applied thereto; the surface of the primary base taking also the shape or contour of the surface to be duplicated. The primary base is carried by a suitable support made of a malleable metal.

I have found out after considerable research and experimentation that a die or mold can be produced in a highly efficient and inexpensive manner by employing the following steps. The article or contour to be duplicated is preferably made or rendered capable of receiving without impairment a metallic deposition, the same is then established as a cathode in an electro-plating bath so that a metallic shell of the foundation metal is built up having the corresponding configuration. I have found that base type metals that can be electrically deposited without great cost such as copper, nickel or cobalt serve the purpose very effectively as foundation metals for building up the metallic shell as any one of these metals has the characteristics desired with reference to ductility, degree of hardness and capability of withstanding without impairment certain physical or chemical actions to which the other superimposed metal may be subjected. The treated article with the electro-deposited foundation or copper shell is cleaned or rendered free from impurities. The back surface of the copper shell is thereafter established as a cathode in a chromium electro-depositing bath in order to bond a backing thereon so as to form the primary base for the die. The article is effectively removed from the composite metallic structure and after freeing the latter from any objectionable matter or impurities, the surface formerly in con-

tact with the article is established as a cathode in an electro-plating chromium bath so that a film of a predetermined thickness is deposited on the copper shell to constitute the face or wearing surface of the die. This chromium film should be of substantially the same over-all thickness of the coatings employed to treat the article and establishing the selected surface as a cathode in the copper electro-plating bath. The resulting composite metallic structure is bonded or fixed to a suitable metallic support or secondary base applied to the primary base or chromium backing. I have found that the application of the secondary base can be effectively carried out before separating the article from the copper shell and that the deposition of the die face or chromium film can be very effectively accomplished after the secondary base has been applied. In addition it is contemplated within the spirit of the invention to remove or dissolve the foundation metal by suitable agents such as by the application of nitric acid and apply to the primary base or chromium backing the hard face metal, building up the same to the thickness not only of coatings employed to treat the article and establish the selected surface as a cathode, but also to the thickness of the layer of the foundation metal, so that the forming tool or die will comprise the hard face metal or working surface and the reinforcing bases or backings.

Referring to the drawing which illustrates a practical application of the invention for producing as a forming tool a die element in which like reference characters are employed to designate like parts; in Figure 1 is shown a pattern or an article to be duplicated which is in the form of a paper weight 10 constructed to the actual contour and dimensions desired to be present in the replicas or facsimiles produced by using the composite cavity die formed by the separable elements 12 and 14, a cross-section of which is illustrated in Figures 2, 3 and 10.

In carrying out my invention for duplicating articles, the surface or contour to be duplicated, which may be of metal, wood, plastic material, wax or other suitable material, is first cleaned with a suitable cleaner or solvent. If the surface of the article is of a material unsuitable to receive a metallic coating, its surface is treated to receive a metallic coating without impairment or is preferably rendered impervious to an electro-plating bath by applying any suitable acid repellent substance as, for example, beeswax which is distributed so as to produce a uniform film or coating thereon. The particular portion of the surface of the treated article selected to constitute or form one of the elements of the die block, such as the lower element 14, is arranged to receive a metallic shell such as by covering the same with current conductive coating for receiving by electro-plating a metallic deposition thereon. I have found that a conductive coating produced by applying a solution containing graphite in suspension or any other suitable conductor, such as plumbago or aluminum paint is very effective. In the embodiment illustrated particularly shown in Figure 4, the base surface 16 of the paper weight 10 which will constitute the lower die section 14 is coated as at 17 with a solution containing graphite so as to give a film of uniform thickness. The uniformity and the thickness of the conductive coating 17 are carefully controlled in order to secure a high degree of accuracy in the duplication of the ex-

act dimensions and contour of the base 16 of the article 10.

The article 10 with its conductive coating 17 is then placed or immersed in an electro-plating bath 19 and established as a cathode so that a layer of copper, nickel, cobalt or other suitable material is deposited on the outer surface of the conductive coating 17, the article being allowed to remain in the bath until a shell or plate 20 of the desired thickness is deposited upon the conductive coating 17. The electro-plating bath 19 should be operated at proper temperature, electric current density, hydrogen ion concentration and a specific gravity density to produce a fine grained, ductile, smooth plate or initial electrical deposition and capable of being modified or controlled so that during the building up of the shell, uneven or irregular portions may be formed at the back or rear of the initial deposition or surface layer, as particularly shown in Figures 5 and 6. I have found that a shell or plate produced by an electro-deposition of a base type metal such as copper serves the purpose very effectively, not only due to their low cost but because they perform the function of readily indicating the wearing of the die during use and also allow the reconditioning of the die, permitting changes when desired without tedious and time consuming operations which render metals of this type very adaptable for the formation of a die following the principles of my invention.

The pattern 10, or contour to be duplicated with the copper plate or foundation shell 20 is removed as a unit from the electro-plating bath 19 and cleaned or freed from impurities by a suitable solvent or degreasing agent and any loose or non-adhering particles are removed therefrom by suitable means.

In carrying out my invention, the copper layer or foundation shell 20 is bonded to a metallic or primary base by preferably immersing the treated article with its foundation metal 20 in a chromium depositing bath, as shown in Figure 7, and the exposed surface or rear face of the metallic shell 20 is established as a cathode for the electro-deposition thereon of chromium layer 22. The layer of chrome is built up to the desired thickness by allowing the article with its metallic shell 20 to remain in the bath for a predetermined period of time, rapidity of the deposition may be regulated and accomplished by changing the temperature concentration of the bath and current density.

The pattern 10 with its deposited electro-plated coatings 20 and 22 is then removed from the chromium bath 19 and rinsed preferably in hot and cold water or other suitable agent to remove objectionable or loose matter.

The article 10 is then preferably separated from the metallic structure 23 formed by the metallic coatings 20 and 22 by any suitable means. I have found that by subjecting the article 10 or metallic structure 23 to heat, due to the difference of expansion between the bonded metal coatings 20 and 22 and the article 10, a very rapid and effective separation can be secured. This separation produces a composite metallic structure formed by the electro-plated coatings 20 and 22 having a front surface corresponding in contour to that of the base 16 of article 10 as is particularly shown in Figure 8.

The surface or face 25 of the metallic shell 20, which has been in contact with the base 16 of the pattern or article to be duplicated, is cleaned with a suitable solvent or degreasing

agent to remove any possible traces of the current conductive substance or graphite coating 17 formerly applied to the surface of the article. The metallic structure 23 is thereafter placed in a chromic acid bath 27 preferably having the particular constituents and incorporating the features set forth in United States Patent No. 1,881,885 of October 11, 1932, and the front face 25 is established as a cathode for the deposition of a chrome film of fine quality deposited at a high current density and temperature. The metallic structure is allowed to remain in the bath until a layer 28 of the very fine metallic chromium of predetermined thickness is deposited on surface 25, the layer 28 having a thickness equal to the thickness of the material covering the surface of the article to be duplicated such as that produced by the coating applied in treating the article and that of the conductive coating, so that the die will have the exact form and accurate dimensions of the model. The composite metallic structure formed by the chromium depositions 22 and 28 covering the soft metallic shell 20 of such metals as copper, nickel or cobalt is removed from the chromium bath and preferably polished to the desired gloss and smoothness after cleaning the same or removing any foreign matter therefrom. The rear surface 30 of the chromium layer 22 is bonded or secured to a suitable support or secondary backing 32 which may have the shape and configuration illustrated in Figure 10 so as to be used as the lower element 14 of the die block. The secondary backing is preferably made of a metal secured by electro-deposition to the rear face 30 of the chromium plate 22, the metal being preferably of malleable character so that machine operations can be performed with ease and speed in order to give the shape and dimensions necessary to conform the machine or press used for producing the facsimiles or replicas. I contemplate the employment of the Goldschmidt process described in United States Patent No. 578,368 or by aluminothermic welding method for bonding the secondary backing to the surface 30 of the multi-layer metallic structure. However, this secondary backing can be produced by "setting" or solidifying molten metal around the metallic structure or by increasing the thickness of the metallic chromic deposition 22 to the desired size.

In the practical application of the invention for producing the lower die element 14, the steps and operations have been described as being performed in a certain predetermined order. However, effective results can be secured by changing their sequence. I have found that in the production of stamping dies or molds having complicated contours or intricate designs, it is very advantageous to apply the secondary backing or base 32 while the composite metallic structure 23 is in contacting engagement with the base 16 of the article 10 and that the step in separating the metallic structure from the article can be carried out after the secondary backing has been bonded or applied thereto. This procedure eliminates any possible distortion of the metallic structure 23 when the secondary base is applied by casting or adding a molten metal thereto which is in some cases very desirable. In addition, this procedure provides means for readily ascertaining any distortion which may have taken place by observing any marks in the outer surface of the article. Moreover, by applying the hard chromium film 28 as a last step in the process, any irregularities or distortion present in

the metallic structure 23 can be compensated for either by changing the contour of the face 25 of the malleable layer or foundation shell 20 or by regulating the thickness of the face metal or chromium film deposited on the surface 25 of the metallic structure.

It should be noted that my invention for duplicating articles by making a shaping tool or die and particularly by the employment of metals having different physical and visual characteristics for the face or wearing surface of the die and its underlying metal, I am able to produce at a very low cost a die or shaping tool having a very hard wearing surface with a means for giving a visual indication which readily apprises the operator of any wearing of the working surface of the die. This indication is very noticeable when the working surface of the die is of chromium and the underlying metal employed is copper, as the latter gives a yellowish cast to the area subject to undue wear before the surface 25 of the copper shell is impaired. The foregoing feature is very desirable because it informs the operator that the die is due for reconditioning before appreciable changes in dimensions and contour have taken place which in many cases destroy the die's usefulness causing its immediate obsolescence as in present practice undue wear of the working areas prevents the possible reconditioning of a die. Moreover, the underlying metal which, as hereinbefore pointed out, is capable of withstanding the application of physical or chemical agents for the removal of the chromium facing without impairment allows that the die could be re-established to its original dimensions and used again by only applying a chromium coating having a predetermined thickness.

The reconditioning of the die when wear of its face metal has taken place can be accomplished very effectively by stripping or removing the hard face metal or chromium film 28 by any suitable means such as by the application of hydrochloric or muriatic acid which will remove the chromium from the foundation metal or copper shell 20 so that the surface 25 will be clear of any chromium layer. After the surface 25 of the foundation metal 20 is free from impurities the same is established as a cathode for the electro-deposition thereon of a new hard chromium film or face layer. The chromium film should have the same thickness as the layer 28 originally applied to the copper shell 20.

I contemplate within the spirit of the invention to produce a die, mold or forming tool which will comprise the hard face metal or fine chromium film 28 bonded to the primary base 22 or to a reinforcing or supporting base structure 32. This type of die can be accomplished by following the steps contemplated to produce the foundation shell 20 and its reinforcing backings prior to the application of the face metal 28, by dissolving or removing the copper shell 20 by the application of nitric acid thereto and thereafter electro-depositing upon the primary base or chromium backing 22 the hard face metal layer 28 building up the chromium deposition to a thickness corresponding to the coatings applied to treat the article and establishing selected sur-

face as a cathode as well as the thickness of the foundation metal 20 so that the die will have the exact form and accurate dimensions of the model.

It is also contemplated within the spirit of the invention that in cases wherein the model or contour to be duplicated is made of a base type metal such as copper, nickel or cobalt, the foundation metal or copper shell 20 and the steps contemplated to produce the same can be dispensed with and a die can be produced by electro-depositing on the selected metallic surface of the model a chromium film of fine quality which will form the face 28 or the wearing surface of the die and thereafter applying suitable reinforcing or supporting bases such as 22 and 32. I contemplate the removal of the article from the chromium face 28 of the die proper by dissolving the article through the use of a suitable chemical agent such as by applying a nitric acid thereto so that the forming tool or die will comprise a chromium layer or film 28 of fine quality constituting the working surface of the die and suitable reinforcing bases or supporting structures bonded thereto.

In the practical application of the invention the method has been described with reference to the production of the lower section 14 of the die block, but it is contemplated that the upper element 12 can be produced by following the steps hereinbefore enumerated. In such case, the upper surface of the paper weight 15 is arranged in lieu of the base 16 to receive the metallic depositions to produce a composite metallic structure having the shape and configuration of the die element 12 of the die block.

It is apparent that, within the scope of the invention, modifications and different arrangements may be made other than is herein disclosed, and the present disclosure is illustrative merely, the invention comprehending all variations thereof.

What I claim is:

1. A die including a foundation metal having a die surface face a layer of chromium of substantially uniform thickness covering the face of said foundation metal; the foundation metal having a different color and degree of hardness than that of said layer, and its face formed to the shape of the working surface of the die; and a chromium backing deposited on the back of said foundation metal.

2. A die including a layer of chromium of substantially uniform thickness constituting the working surface of the die and being bonded to a cobalt supporting shell; the supporting shell formed to the shape of the working surface of the die made by electrolytic deposit; and a chromium backing bonded on the rear surface of said shell.

3. A die formed of superimposed metals including a layer of chromium of substantially uniform thickness constituting the working surface of the die; a metallic foundation of nickel bonded to said chromium layer the face of the metallic foundation formed to the shape of the working surface of the die; a layer of chromium bonded to the rear surface of said metallic foundation forming a covering therefor; and a metallic backing bonded to said chromium covering.

CARL J. WELCOME.
